United States Patent Office

Des. 198,818
Patented Aug. 4, 1964

198,818

CAP FOR CONTAINERS

Morton B. Stull, Boonton, N.J. (½ Stull Engraving Co.,
221-223 Banta Ave., Garfield, N.J.)

Filed Jan. 28, 1963, Ser. No. 73,330

Term of patent 14 years

(Cl. D58—26)

Fig. 1

Fig. 4

Fig. 2

Fig. 3

FIGURE 1 is a side elevational view of a cap for containers, embodying my new design.

FIGURE 2 is a top plan view thereof.

FIGURE 3 is a bottom plan view thereof.

FIGURE 4 is a diametric section taken on the line 4—4 of FIG. 2.

The cap is shaded to indicate contrast in surface texture.

I claim:

The ornamental design for a cap for containers, as shown and described.
